(57) **CLAIM**

The ornamental design for an aircraft with skylight, as shown and described.

DESCRIPTION

FIG. 1 is a perspective view of the aircraft with skylight showing our new design;

FIG. 2 is a left view of the aircraft with skylight of FIG. 1; FIG. 3 is a side expanded perspective view of the encircled portion in FIG. 1; and,

FIG. 4 is an expanded side view of the encircled portion in FIG. 2.

The broken lines shown in FIGS. 1-4 depict portions of the aircraft with skylight that form no part of the claimed design. The light dash-dot lines shown in FIGS. 1 and 2 depict boundary lines that form no part of the claimed design. The additional heavy dash-dot lines surrounding the detail views are for annotative purposes only and form no part of the claimed design.
